E. L. PRATT, OF BOSTON, MASSACHUSETTS.

Letters Patent No. 76,247, dated March 31, 1868.

IMPROVED NUT-CRACKER.

The Schedule referred to in these Letters Patent and making part of the same.

TO ALL WHOM IT MAY CONCERN:

Be it known that I, E. L. PRATT, of Boston, in the county of Suffolk, and State of Massachusetts, have invented an Improved Arrangement of Levers for Operating Jaws for Nut-Crackers, &c.; and I do hereby declare that the following, taken in connection with the drawings which accompany and form part of this specification, is a description of my invention sufficient to enable those skilled in the art to practise it.

My invention relates to the method of combining levers to operate jaws or similar devices, which are jointed at one end, and close and spread open at the other, as do the members of nut-crackers, shears, pincers, and similar tools.

My invention consists in combining, with one jaw or member of such a tool or instrument, a bent lever, one arm of which (made very short) is jointed to and acts upon one of the jaws, through pressure upon the end of the long arm of the lever, the lever being hung upon a movable fulcrum mounted in bearings or links, jointed to the opposite jaw or member, so that while the fulcrum of the lever is kept at a fixed distance from the opposite jaw, it is enabled to swing back as the short arm of the lever depresses the jaw to which it is connected.

The drawing represents my invention embodied upon a pair of jaws to be used as nut-crackers.

a and *b* denote two jaws, (which in this case are made, one stationary and one movable,) they being jointed together at *c*. *d* denotes the handle or lever by which the jaws are brought towards and separated from each other. This lever is fulcrumed in bearings or links *e*, (one on each side of the jaw,) which links are preferably jointed to the lower jaw *a*, and so as to swing upon the joint-pin *f*. A short arm, *g*, of the lever, extends down to the adjacent jaw *b*, and is jointed thereto by a pin, *h*, while the long arm of the lever extends rearwards over said jaw.

When the jaws are open, the lever and its fulcrum-link are in the position denoted by red lines, the short arm of the lever inclining from a vertical position. If the lever-handle be now depressed, the arm *g*, in assuming a vertical position, forces down the jaw *b*, and compresses, breaks, or cuts the matter placed between the jaws, the fulcrum *e* swinging back to allow the arm *g* to come into vertical position, or into right-angular position to the jaw upon which it acts.

By thus making the fulcrum *e* movable, (while jointed to or with respect to the jaw *b*,) I am enabled to joint the lever directly to the jaw *b*, and to obviate the wear by friction which would be caused if the bearings *e* were made stationary, with the short arm of the lever acting upon the surface of the jaw *b* like a wiper or cam.

Instead of connecting the fulcrum to the stationary jaw by a straight link, I curve the links, as seen in the drawing, and thereby make the acting surfaces of the jaws accessible along the whole or nearly the whole length thereof.

I claim, in combination with jointed jaws *a* *b*, the lever *d*, jointed to one jaw *b*, and hung upon a swinging fulcrum, substantially as described.

I also claim connecting the lever to the jaw *a* by the curved link or links *e*, substantially as and for the purpose set forth.
